(57) **CLAIM**

The ornamental design for an electrical housing, as shown and described.

DESCRIPTION

FIG. 1 is an exploded front-top-right perspective view of an electrical housing showing our new design.

FIG. 2 is an exploded rear-top-right perspective view of the electrical housing shown in FIG. 1.

FIG. 3 is a front-top-right perspective view of the electrical housing of FIG. 1, shown with the covers attached.

FIG. 4 is a rear-top-right perspective view thereof.

FIG. 5 is a front view thereof.

FIG. 6 is a top view thereof.

FIG. 7 is a rear view thereof.

FIG. 8 is a bottom view thereof.

FIG. 9 is a right side view thereof; and,

FIG. 10 is a left side view thereof.

The broken lines in the drawings show portions of the electrical housing that form no part of the claimed design. The dot-dash lines showing the exploded structures in FIGS. 1 and 2 are shown for clarity of disclosure and indicate the path along which the removable covers have been exploded away from the remainder of the electrical housing and form no part of the claimed design.
